UNITED STATES PATENT OFFICE.

HUGO BAUER, OF VIENNA, AUSTRIA, ASSIGNOR OF ONE-HALF TO C. SCHEMBER & SÖHNE, OF VIENNA, AUSTRIA.

MECHANICALLY-OPERATED GRATE.

1,223,661.

Specification of Letters Patent.

Patented Apr. 24, 1917.

Application filed November 6, 1915. Serial No. 59,912.

To all whom it may concern:

Be it known that I, HUGO BAUER, an engineer by occupation, subject of the Emperor of Germany, residing at 51 Gentzgasse, 5 Vienna, XVIII, in the Empire of Austria, have invented certain new and useful Improvements in Mechanically-Operated Grates, of which the following is a specification.

10 In the mechanically operated grates already known, the movement of the bars is generally such as to cause each point of the bar to describe a closed curve, the result being that the fuel is moved in two directions 15 vertical to each other.

Moreover, in arrangements of the said kind, the inertia of the fuel is inadequate to cause the fuel to travel across the whole grate, or to obtain a uniform deposit of 20 ashes, or finally to secure a good regulation of the supply from the hoppers. For this reason, the inertia of the fuel requires to be supplemented by the gravity thereof and, in consequence, the grate must always be arranged 25 at a greater or smaller inclination. Notwithstanding, the movement of the fuel and the clinkers is not efficient enough to prevent the fuel either from caking, sticking to the grate and partially choking the useful 30 grate area. In addition, the speed at which the fuel travels across the surface of the grate depends upon many circumstances, such as the speed of the grate bar, the inclination of the surface of the grate, the 35 curved line described by the grate, the manner of charging the fuel, and the like, some of which cannot be controlled, so that the said speed cannot be regulated with entire safety. It consequently follows that 40 different kinds of fuel cannot be employed upon one and the same grate, since several of the aforementioned circumstances do not admit of being altered or controlled at will.

The present invention relates to a mechanically operated grate, in the case of which, in contradistinction to the arrangements hitherto known, the movement of the bars takes place in one direction only, so that they merely execute a straight-linear movement comprising a slow forward and a sudden return movement back into the initial position.

This new and improved construction obviates the necessity of assisting the movement 55 of the fuel by the gravity thereof, when the

bar is executing the advance motion, in order to obtain a sufficient feed space for the fuel as soon as the bar carries out the return motion, for, owing to the suddenness with which the bar returns into its initial position, any corresponding movement of the fuel is prevented by the inertia thereof, so that the advance of the fuel for a certain unit of time, depends entirely upon the distance traversed during a certain unit of time 60 by the grate bar; in other words, it depends upon the said distance and the number of advance motions executed.

Under these circumstances it is possible by regulating both the distance and the number 70 of advance motions to be executed, to exactly dimension the movement of the fuel, irrespective of other circumstances, so that different kinds of fuel may be employed on one and the same grate.

It is likewise understood that the grate does not require to be arranged at any inclination whatsoever. The simple straight-linear movement, the possibility of a horizontal arrangement of the grate, and the 80 easy mode of regulating the speed at which it is intended the fuel shall travel across the grate, constitute advantages such as are not obtainable by simple means in connection with the constructions hitherto known.

The accompanying drawings illustrate, by way of example, a constructional embodiment of my invention, Figure 1 showing a horizontal section and Fig. 2 a plan view of the grate, while Fig. 3 shows a cross-section, 90 on an enlarged scale, of the grate bars and the device by means of which they are actuated.

As will be seen from these drawings, the single bars *a* are movably disposed on the transverse bearers *b*, *b'*. Each of the bars *a* is provided with a projection *c* adapted to be taken along by a corresponding tooth or projection *d* on the shaft *e*. The shaft *e* is actuated by a transmission by aid of the pulley *f*. In addition, each bar is provided with a bolt *g* surrounded by a compression spring *h*, the movement of which is limited on the one hand by the abutment *i*, screwed on to the bolt *g*, and on the other hand, the wall-portion *k* of the furnace. A hopper *l* is arranged above the grate, having two openings provided with fire doors *m* which, in the event of the mechanical stoking of the grate getting out of order, will 110

permit of the fuel being charged and raked by hand.

The furnace is closed above the grate by means of a movable wall n , provided with a feed regulator o adapted to be adjusted to any height desired, and thus controlling the depth of the fuel bed. The front wall of the furnace is arranged to swing about the axis p and is preferably weighted by a weight q in such a manner as to allow of the said axis being easily rocked.

For the purpose of removing the clinkers, a small auxiliary grate s is fixed to the rear end of the main grate. The said grate s is supported by the transverse bearers b' , b'' and consists either of a single plate or a plurality of adjoining plates s^1 , s^2 , s^3 . These plates are likewise preferably movable, and that in a direction opposite to the movement executed by the grate bars, for the purpose of effecting the removal of the clinkers. To this end, each plate is suitably connected to a rod t which, in a manner similar to the bolt g , carries a spring h' at its front end abutting against a strap fixed to the front wall of the furnace and compressed by a collar i' , fixed to the rod t , when this latter is shifted outward. Moreover, each of the rods is provided with a projection e' , which is likewise taken along by a tooth or projection d' , fixed to the shaft e , from which it is subsequently again released.

Since the number of plates s^1 , s^2 , s^3 is considerably less than the number of the grate bars, a movement of the auxiliary grate will only be effected at considerable intervals of time.

For the purpose of moving the plates, s^1 , s^2 , s^3 , the same teeth or projections d may be employed as for moving the grate bars; however, if desired, a special set of teeth or projections d' may be arranged on the shaft e between the teeth or projections d . A movement opposite to the one executed by the grate bars, is preferably obtained by arranging the rods t at the opposite side in relation to the shaft e . The path described by the rods t is preferably longer, this being obtained by correspondingly dimensioning the projections e' . Furthermore, in order to always secure a larger interval of time between each two movements of the same plates, the teeth or projections d , serving to move the grate bars, are disposed to project radially from either side of the shaft, to the end that, each time the shaft e completes a revolution, the grate bars are shifted forward twice, while at the same time (since the teeth or projections d' are disposed only on one side of the shaft) the bars t will be only actuated once.

The shaft e is arranged transversely to the grate bars a , and all the teeth or projections d and d' , carried thereon, are so distributed as to cause the least number of rods

possible to be moved simultaneously. In the event of teeth or projections d' being provided for the plates s^1 , s^2 , s^3 , on the shaft e between the teeth or projections d and similar thereto, then such said teeth or projections d^1 will have to be distributed in a like manner to suitably prevent the plates from being moved at one and the same time.

When the shaft is rotated, then alternately always one grate bar is shifted forward by the teeth or projections d , these taking along the projections e while at the same time the springs h are compressed. The fuel resting on the moving grate bar, is thus carried along in the course of the said slow forward movement. Thus by shifting the single bars forward in succession, the caking of the fuel will likewise be prevented.

After the tooth or projection d has moved past the projection e , the grate bar is jerked back under the action of the spring h , the fuel remaining in its place in consequence of its inertia. The advance movement accordingly effected, almost entirely corresponds to the path described by the grate bar.

The depth of the fuel bed is at the same time regulated by the feed regulator o , which is adapted to slide up and down in guides arranged in the movable wall n .

After the fuel has been consumed, it is thrown by the grate bars on to the plates s^1 , s^2 , s^3 , whence it is gradually dropped into the ash-pit u as a result of the movement imparted to the plates.

If, for some reason, the actuating device for the grate or the grate bars should happen to get out of order, then the movable front wall n is rocked about its axis p until it is in a horizontal position, in which it is then secured. The stoking and raking can then be effected through the openings m formed in the hopper l .

What I claim is:

1. A mechanically operated grate comprising longitudinally movable, substantially horizontally arranged grate-bars, supports therefor, springs for holding said grate-bars in their normal positions, a continuously rotated actuating means for periodically moving said grate-bars singly and at different times against the action of their springs, the springs rapidly returning the grate-bars to their normal positions, a supplementary grate arranged at the rear of said grate bars for receiving the clinkers, said supplementary grate comprising longitudinally movable horizontal plates, and means for periodically moving said plates back and forth opposite to the movement of said grate-bars.

2. A mechanically movable grate comprising longitudinally movable, substantially horizontally arranged grate-bars, supports therefor, means, such as springs, for holding the grate-bars in their normal positions, an

- actuating means for moving said grate-bars against the action of their springs, the springs rapidly returning the grate-bars to their normal positions, a supplementary 5 grate arranged at the rear of the said grate-bars for receiving the clinkers, said supplementary grate comprising substantially horizontally arranged, longitudinally movable plates, rods pivoted to said movable plates, 10 springs on said rods holding the plates in their normal positions, projections on said rods, and an actuating means adapted to periodically engage said projections to move the said rods and thereby the said plates 15 against the actions of their springs, the latter rapidly returning the said plates to their normal positions.
3. A mechanically operated grate comprising longitudinally movable, substantially 20 horizontally arranged grate-bars, supports therefor, means, such as springs, holding the said grate-bars in their normal positions, projections on said grate-bars, a supplementary grate arranged at the rear of said grate-bars for receiving the clinkers, said supplementary 25 grate comprising longitudinally movable, substantially horizontally arranged plates, rods pivoted to said plates, springs on said rods, holding the rods and the said plates in their normal positions, projections on said rods, a rotatable shaft, projections thereon, adapted to engage the 30 projections on said rods and on said grate-bars, so as to periodically move the said plates and the said grate-bars in opposite directions, the springs rapidly returning the said plates and the said grate-bars to their normal positions, the arrangement being 35 such that the grate-bars are moved twice to each movement of the said plates and a source of power for rotating said shaft.
- In testimony whereof I have hereunto set my hand in presence of two subscribing witnesses.

HUGO BAUER.

Witnesses:

ARTHUR LINDENSTEAD,
AUGUST FUGGER.

springs rapidly returning the said plates and the said grate-bars to their normal positions, and a source of power for rotating said shaft.

4. A mechanically operated grate comprising longitudinally movable, substantially horizontally arranged grate-bars, supports therefor, means, such as springs, holding the said grate-bars in their normal positions, projections on said grate-bars, a supplementary 40 grate arranged at the rear of said grate-bars for receiving the clinkers, said supplementary grate comprising longitudinally movable, substantially horizontally arranged plates, rods pivoted to said plates, 45 springs on said rods, holding the rods and the said plates in their normal positions, projections on said rods, a rotatable shaft, projections thereon, adapted to engage the 50 projections on said rods and on said grate-bars, so as to periodically move the said plates and the said grate-bars in opposite directions, the springs rapidly returning the 55 said plates and the said grate-bars to their normal positions, the arrangement being 60 such that the grate-bars are moved twice to each movement of the said plates and a source of power for rotating said shaft.
